PHILIP N. WOLISTON, OF SPRINGFIELD, OHIO, ASSIGNOR TO HIMSELF AND FERRELL, LUDLOW, AND RODGERS.

Letters Patent No. 80,890, dated August 11, 1868.

IMPROVED BRICK-MACHINE.

The Schedule referred to in these Letters Patent and making part of the same.

TO ALL WHOM IT MAY CONCERN:

Be it known that I, PHILIP N. WOLISTON, of Springfield, in the county of Clarke, and State of Ohio, have invented a new and useful Improvement in Brick-Machines; and I do hereby declare that the following is a full, clear, and exact description of the same, reference being had to the annexed drawings, making part of this specification, in which—

Figure 1 is a perspective view,

Figure 2 is a transverse section, and

Figure 3 is a vertical section.

The same letters in all the figures indicate the same parts.

This invention relates to that class of machines for making bricks, in which the clay is pressed through a tubular die in a continuous piece, to be afterwards cut into bricks; and it consists in placing, in the central part of such tubular die, parallel rods, which, running longitudinally, terminate near the mouth of the die, so that the clay, in being forced through the die, shall be retarded in the centre, and thus made to pass uniformly out of the machine; also, in giving such form to the mouth of the die that the corners of the prism of clay shall first emerge from the die, the sides being longer retained; also, in so attaching the rods to a bridge fastened to the mouth-plate of the machine that they may be removed, as well as the die which is bolted to the outside of said plate, so that a core being attached to the bridge, the same machine may be used either for making brick or tile.

A practical difficulty in operating this class of machines has been found to be, that as the friction of the clay against the sides of the die is greater than that between the particles of clay, the central part of the prism would be pushed out faster than the sides, which are retarded. So, also, the friction at the corners being greater in proportion to the mass of clay than along the sides, the delivery of the corners is retarded, and the prism of clay, as delivered, is distorted and of unequal density, so that, in drying, the bricks crack at the angles, and the centre being denser than the edges, the latter would shrink most in drying, so that the brick becomes convex on the faces.

Precisely opposite results are desired. The clay should be delivered so that the edges shall be sharp, and the centre should be less dense than the edges, so that in drying the bricks shall shrink most at the centre, leaving the faces slightly concave, and the edges sharp and well defined, and without cracks. These results are attained by the following arrangement of parts.

In the annexed drawing, A is the die, through which the clay, after being properly tempered, is forced in a continuous prismatic block, to be afterwards cut into the proper length for bricks. This die is formed of an external cast-iron case, and an internal lining of polished metallic plates, glass, porcelain, or other suitable material, to reduce friction. I prefer to use glass for this purpose. The lining, being made smaller in diameter than the case, may be attached by filling the intermediate space with plaster-of-Paris or other cement. The die is bolted to the mouth-plate E of the machine. The bridge C is also bolted to the inner face of the same plate. The rods D, placed parallel with one another, are attached to the bridge by screw-threads, and are placed in the middle part of the chamber of the die, resting longitudinally therein. They may be made tapering to the point, and either terminated a little short of the mouth of the die or continued beyond it. In the former case, the prism issuing from the die will be a compacted mass of clay, or in the latter, it may be left perforated longitudinally, which may be found to be useful in drying the bricks. The friction on the faces being, as already stated, greatest, these rods are intended to cause a resistance to the passage of the clay through the centre of the die, and occasion a uniform motion in the mass of clay passing through the die. The rods also, by leaving spaces into which the clay is expanded in issuing from the die, leave the centre of the prism less dense than the edges, so that, shrinking in drying, the brick shall assume a convex form on its faces, as the centre will shrink more than the edges.

The rods, being attached by screws to the bridge, may be removed, and a core be attached to the bridge to form tile, so that, with slight alteration, the same machine may be used for making brick or tile.

The mouth of the die is ordinarily made square. Instead of this, I cut away the plates at the corners so as to leave projections at the middle of the sides and ends at A', so that as the clay passes through the die the corners shall first be relieved, so that the clay may be packed compactly into the angles, and pass from the die without straining or distorting the corners.

I have ascertained by experiment that five rods will answer in practice, but do not limit myself to any precise number, the number required being dependent upon the character of the clay, and its condition.

What I claim as my invention, and desire to secure by Letters Patent, is—

1. The die A, in combination with rods D, arranged in relation thereto substantially as and for the purpose set forth.

2. Forming the mouth of the die with projections in the middle of the sides at A', substantially as and for the purpose set forth.

In testimony whereof, I have signed my name to this specification in the presence of two subscribing witnesses.

PHILIP N. WOLISTON.
